UNITED STATES PATENT OFFICE.

ROBERT ALLEN HEFFLEY, OF DENVER, COLORADO.

WATER-HEATER.

No. 872,129.

Specification of Letters Patent.

Patented Nov. 26, 1907.

Application filed August 11, 1906. Serial No. 330,193. Renewed October 16, 1907. Serial No. 397,676.

To all whom it may concern:

Be it known that I, ROBERT ALLEN HEFFLEY, a citizen of the United States, residing at Denver, in the county of Denver and State 5 of Colorado, have invented a new and useful Water-Heater, of which the following is a specification.

This invention relates to a device for heating water, other liquids, and air by the use of 10 steam or other suitable heating media, and it relates more particularly to a device of this character which is of simple, inexpensive and practical construction, and highly efficient in operation.

15 One of the objects of the invention is the provision of a heater in which the fluid to be heated is gradually brought to the point of entrance of the steam and is then returned so as to prevent rapid condensation of the 20 steam and effect a more even heating of the fluid.

A further object is the employment of a 25 plurality of concentric tubes and a common distribution chamber arranged to receive the fluid being heated as it passes out of the inner set of tubes and to deliver the fluid, after the same has been completely mingled, to the outer set of tubes. This chamber enables the fluid or liquid to be freed from impurities 30 and also permits of the temperature of the liquid being equalized before passing to the outer tubes.

Another object of the invention is to provide separate chambers at one end of the device by which the cold water enters and heated water leaves, the arrangement being such that the cold water passing through the inner tubes is subjected to the heating effect of the hot water before being subjected to the 40 steam. This initial heating of the cold water tends to reduce the condensation of the steam and also permits of the water being so highly heated as to free it from impurities and kill the germs therein while passing 45 through the steam space of the device. The cooling of the hot water by the entering cold water serves to reduce the temperature sufficiently for use, as in scrubbing floors, for instance.

50 With these objects in view, the invention comprises the various novel features of construction and arrangement of parts, which will be more fully described hereinafter, and set forth with particularity in the appended 55 claims.

In the accompanying drawing, illustrating

one of the embodiments of the invention, is shown a longitudinal section of the device with portions broken away.

The present device is designed for several 60 uses, such as a water heater and purifier to be used in connection with boilers, a water or air heater for heating buildings, or for drying devices, or as a hot water heater for furnishing water for scrubbing purposes, laundry 65 work, and the like.

Referring to the drawings, 1 designates a steam cylinder or jacket having heads 2 suitably secured thereto and each provided with a threaded flange 2' for engagement with the 70 correspondingly threaded ends of the cylinder, as shown. The cylinder is preferably made of iron and may be of any desired size. Extending longitudinally of the cylinder are a plurality of tubes 3 that pass at their ends 75 through the heads and are expanded down upon the outer surfaces thereof. Steam or other heating fluid is admitted to the cylinder at one end through the inlet conduit 4 and circulates freely around the tubes 80 3 to effectively heat the same. The lower, or opposite, end of the cylinder is provided with a valved drain 5 to permit the water of condensation to be drawn off.

At one end of the cylinder, preferably the 85 lower, when the cylinder is to be used upright, is a casing 6 which is extended below and is preferably formed integral with the lower head 2, said casing being provided with a cap 7 having a removable cover 8. 90 The cap 7 and short casing 6 are each provided with a circumferential flange 9 perforated to receive bolts 10 which hold the two together. Intermediate the flanges is a gasket 11 for preventing leakage. The upper 95 end of the short cylinder or casing 6 is provided with the flange 2' so as to screw on the external thread 12 on the lower end of the cylinder 1, as before described. Instead of a screw joint between the jacket 1 and short 100 cylinder 6, a flange joint may obviously be employed, if desired. The casing 6 is divided into separate chambers or compartments by means of a partition 13, preferably formed integral with the cap 7 such partition 105 forming a head for supporting the inner tubes 14. The lower ends of the inner tubes are threaded, or otherwise suitably secured, in the wall 13, and from the wall the tubes extend upwardly through the chamber 15 of 110 the casing 6 and into the outer tubes 3, said inner tubes being extended slightly short of

the upper ends of the outer tubes and provided with spring fingers 15' which bear against the outer tubes and serve to center said inner tubes. The inner tubes are thus 5 in communication with the lower chamber or compartment 16 of the cap 7, and the corresponding ends of the outer tubes are in communication with the upper compartment 15. The upper ends of the inner tubes are open, 10 so that fluid can flow between said tubes and their respective inclosing outer tubes. In order to effect a better heating of the water, or other medium to be heated, with less condensation of the steam, the water is led into 15 the steam space of the cylinder by means of the set of inner tubes, and hence the compartment 16 forms an inlet chamber to which the water is admitted by the conduit 17. The compartment 15, which forms the outlet 20 chamber of the device, discharges the heated water through the conduit 18.

At the upper end of the cylinder a distributing chamber is provided with which the upper ends of the tubes communicate. This 25 chamber 19 is formed by a cap 20 that is screwed on or otherwise suitably secured to a flange on the upper head of the cylinder 1. When the cap is screwed on, as shown, a squared extension 21 is provided for the 30 reception of a wrench for removing or replacing the cap. One of the objects of the chamber 19 is to permit of the scum and impurities in the water being collected therein. An outlet conduit 22, which is provided with a valve 35 (not shown) pierces the extension 21 and serves to draw off the impurities.

In operation, steam is admitted to the jacket 1 through the pipe 4, the quantity of steam being controlled in any suitable manner. The steam filling the space around the 40 outer tubes 3 and between the heads 2 operates to heat the water passing through the outer tube and through the chambers 15 and 19. The water flowing into the device passes up through the inner tubes 14 and is heated indirectly by the steam through the 45 heated water passing through the space between the inner and outer tubes. Since both the inner and outer tubes are in communication with the upper chamber 19, the water can freely pass from the inner tubes to said chamber and the several streams thoroughly 50 intermingling. This permits of the water in the different parts of the chamber 19 being 55 equalized as to temperature before passing down through the outer tubes. This is an important feature, for the reason that one side of the heating device may be exposed, in some cases, to a greater degree of cold, so 60 that the water in flowing up the tubes along the relatively cold side will be heated to a less extent. The lower or outlet chamber 15 has the same function of equalizing the 65 temperature of the water before passing out through the discharge pipe. From the up-

per chamber 19 and from the outlet ends of the inner tubes, the water flows down through the outer tubes and is further subjected to the heating effect of the steam, so that by the time it reaches the outlet chamber 15, it will 70 be heated to the desired extent. It will be noted that the lower portions of the inner tubes will have a cooling effect on the hot water in the chamber 15. This is not objectionable, for the reason that it permits of 75 the water being heated to such a high degree as it passes down through the steam cylinder as to free it of alkaline substances or other impurities and germs, and to be cooled by the cold water passing through the lower end 80 of the inner tubes, so that the water can be used for such purposes as scrubbing, without being too hot for the hands.

I have described the principle of operation of the invention, together with the apparatus 85 which I now consider to be the best embodiment thereof, but I desire to have it understood that the apparatus shown is merely illustrative, and that various changes may be made, when desired, as are within the scope 90 of the invention.

What is claimed is:—

1. In a device of the class described, the combination of a jacket, a compartment at one end thereof, and sets of telescopic tubes 95 communicating at corresponding ends with each other and with the compartment.
2. In a device of the class described, the combination of a jacket, separate compartments at one end, a single compartment at 100 the opposite end of the jacket, and a set of tubes extending from each of said separate compartments and communicating with the said single compartment.
3. In a device of the class described, the 105 combination of a cylinder adapted to contain a heating fluid and having oppositely disposed heads, a distributing chamber disposed above one of the heads, tubes connecting said heads, a casing at the opposite head of the cylinder, a partition dividing the casing into separate compartments, and tubes secured to the partition to receive the liquid to be heated from one of said compartments and extending through the other compartment 110 for communication with the distributing chamber.
4. In a device of the class described, the combination of a cylinder adapted to contain a heating fluid, a casing at one end of the cylinder, a partition dividing the casing into 115 separate inlet and outlet compartments, a chamber at the end of the cylinder opposite from the casing, tubes extending from said chamber to the outlet compartment, and tubes communicating with the said chamber and the inlet compartment.
5. In a device of the class described, the combination of a cylinder adapted to contain a heating fluid, a casing secured at one end of 130

the cylinder and composed of separate sections removably secured together and having a wall between them for dividing the casing into two separate compartments, an inlet 5 conduit leading to one of the compartments, an outlet conduit leading from the other compartment, separate sets of tubes communicating with the said compartments, and a chamber between one set of tubes and the 10 other.

6. In a device of the class described, the combination of a cylinder adapted to contain a heating fluid, a casing secured to one end of the cylinder, a partition dividing the casing 15 into separate inlet and outlet compartments, tubes extending through the cylinder and communicating with the outlet compartment, tubes extending through the first mentioned tubes and communicating with the inlet compartment, a chamber at the opposite end of the cylinder with which the inner and outer tubes communicate, and means arranged to permit impurities to be discharged from the 20 said chamber.

7. In a device of the class described, the combination with a cylinder adapted to contain a heating fluid, a casing secured to one end of the cylinder, a partition dividing the casing into separate inlet and outlet compartments, tubes extending through the cylinder and communicating with the inlet compartment, tubes extending through the first mentioned tubes and communicating with 25

the inlet compartment, spring fingers carried by some of the tubes and bearing against the 35 interior walls of the adjacent tubes, a chamber at the opposite end of the cylinder with which the inlet and outlet tube communicate, and means arranged to permit impurities to be discharged from said chamber. 40

8. In a device of the class described, the combination with a cylinder adapted to contain a heating fluid, a casing secured to one end of the cylinder, a partition dividing the casing into separate inlet and outlet compartments one of which is provided with a 45 detachable cover, tubes extending through the cylinder and communicating with the inlet compartment, tubes extending through the first mentioned tubes and communicating with inlet compartment, the inner tubes terminating short of the outer tubes and having laterally extending spring fingers adapted to bear against the interior 50 walls of said outer tubes, a chamber at the opposite end of the cylinder with which the inner and outer tubes communicate, and means for permitting the discharge of impurities from said chamber. 55

In testimony that I claim the foregoing as 60 my own, I have hereto affixed my signature in the presence of two witnesses.

ROBERT ALLEN HEFFLEY.
